FOUNTAIN PEN

Martiniano Flore, Manila, P. I.

Application October 2, 1939, Serial No. 297,581

1 Claim. (Cl. 120—47)

The invention relates to a writing pen and more especially to a fountain pen of the self-filling type.

The primary object of the invention is the provision of a pen of this character, wherein the flow ducts for ink are maintained clean with resultant free flow of ink in the use of the pen and on the charging of the latter with ink a complete quick filling can be had.

Another object of the invention is the provision of a pen of this character, wherein valves or other cut-offs are dispensed with for control of ink flow, the ink being stored in a chamber built within the barrel or cylinder of the pen and in this fashion relieving the latter of a collapsible sack or rubber bag which deteriorates from age and the action of ink thereon.

A further object of the invention is the provision of a pen of this character, wherein rubber parts are entirely dispensed with and the pen points can be automatically cleaned without requiring the removal of said point or its feeder part in association therewith.

A further object of the invention is the provision of a pen of this character, wherein a piston on reverse strokes thereof draws ink into the pen and forces the ink under pressure into a storage chamber for the feeding of such ink to the point in the use of the pen.

A still further object of the invention is the provision of a pen of this character, which is simple in its construction, thoroughly reliable and efficient in operation, assured of a maximum capacity of ink and will accomplish the filling operation rapidly and also will give further satisfactory service, being simple in construction and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention and pointed out in the claim hereunto appended.

In the accompanying drawing:

Figure 1 is a vertical longitudinal sectional view through a pen constructed in accordance with the invention.

Figure 2 is an enlarged fragmentary vertical longitudinal sectional view through the cap end of the pen.

Figure 4 is a sectional view taken on the line 4—4 of Figure 2 looking in the direction of the arrows.

Figure 3 is a fragmentary vertical longitudinal

5—5 of Figure 1 looking in the direction of the arrows.

Figure 6 is a sectional view taken on the line 6—6 of Figure 3 looking in the direction of the arrows.

Similar reference characters indicate corresponding parts throughout the several views in the drawing.

Referring to the drawing in detail, A designates generally the fountain pen constructed in accordance with the invention and comprises a cylindrical body 10 of uniform cross sectional size 15 and constituting the barrel or casing for the pen. This body 10 has opposite open ends internally threaded, one being detachably engaged by a sleeve-like feed cap 11 while the other end accommodates therein a removable closure cap 12. 20 The feed cap 11 has fitted therein a feeder member 13 and a pen point 14, respectively, the cap 11 being provided with a suitable clearance for snugly accommodating both the feeder member and the point. The body 10 creates interiorly 25 thereof between the caps 11 and 12 an ink chamber 15 and operating in this chamber is a pull and push piston 16, its operating stem 17 plays snugly through a center clearance therefor in the cap 12 and has fixed thereto at its outer end an 30 operating knob or grip 18 which constitutes an inverted cup-shaped cover piece separably engageable over the cap 12, the engagement being had through screw threads 19 therebetween. The piston 16 is adapted to be reciprocated within the 35 chamber 15 in the filling of the pen A.

Formed longitudinally in the wall of the body 10 at diametrically opposite points thereof are bypasses or diverting passages 20, these at opposite ends through the ports 21 and ducts 22 communicate with the chamber 15 through the body 10 and the cap 11 through the reduced inner end 23 thereof with the feed ways or conduits 24 provided in the feeder member 13 for the discharge of air from within the chamber 15 through 45 these conduits 24 to without the pen. The feeder member 13 longitudinally thereof intermediate with respect to the conduits 24 has provided therein an inlet conduit 25 which opens through the outer end of said feeder member and also 50 through the inner end thereof into the chamber 15. Ink is drawn in through this conduit 25 to within the chamber 15 next to the piston 16 at the side thereof confronting the cap 11 on the outstroke of said piston. The air at the other 55

side of the piston within the chamber 15 is expelled through the passages or by-passes 20 and the conduit 24 in the feeder member 13 to without the body 10. The body 10 concentrically of the 5 reduced end 23 of the cap 11 has feeder channels 26 in the inner face thereof, these allowing ink within the chamber 15 above the piston 16 to gravitate past the said piston and be delivered through the feeder conduit 25 to the pen point 14 when the piston 16 is forced fully inwardly of the chamber 15 of the body 10.

When the piston 16 is moved inwardly of the chamber 15 subsequent to its outward stroke, the ink within this chamber 15 is forced through 15 the by-passes or passages 26 back into the chamber 15 rearwardly of said piston 16.

To fill the pen the cap 11 with the point 14 and feeder therein is dipped into a bottle of ink. Now on unscrewing the grip 18 from the cap 12 20 an operator can pull the piston upward and ink from the bottle will flow into the chamber 15 below the piston 16 through the conduit 25. On account of the vacuum created by the displacement of the piston 16 the air in the chamber 15 25 will pass out through the ports 21, by-passes 20, ducts 22 and conduits 24 until the piston is in its uppermost or outermost position. A partial outermost stroke of the piston is indicated by dotted lines in Figure 1 of the drawing. By pushing the 30 piston downwardly in the chamber 15 ink accumulated under the piston 16 will pass out with pressure through the conduit 25 and the chamber 15 above the piston will have created therein a vacuum due to the downward stroke of the said piston thus the ink within a bottle will flow or 35 rush through the conduit 24, ducts 22, by-passes 20, ports 21 into the chamber 15 resulting in filling the fountain pen with ink equal to the volume of air displaced in the upward motion of the said piston. By repeating the push-pull op-

eration of the piston 16 more than once has the advantage of cleaning the ducts and passages of the fountain pen as the liquid has to flow there-through under pressure.

In writing with the pen ink in the chamber 15 5 will freely flow through the channels 26 from above the piston 16 and be delivered to the pen point through the conduit 25.

It is preferable to have the external surface of the body 10 of octagonal formation for convenience in the handling of the pen for writing purposes.

What is claimed is:

A pen of the kind described comprising a barrel provided with a chamber and intake passages, respectively, the intake passages being disposed diametrically opposite each other and lead from one end of the barrel to the other and communicate with the chamber at the said other end of the said barrel, a feeder member releasably fitting the barrel and having passages opening directly into the chamber and into the said intake passages, respectively, a removable closure cap fitting said barrel at the end opposite the feeder member and having a portion projected 25 outwardly from the barrel, a pen point adjacent to said feeder member and cooperating therewith, a piston operating within the chamber and having a stem slidably fitting the closure cap, a cap on said stem and removably engaged with the closure cap at the portion extended beyond the barrel and having a recess for accommodating the said extended end of the closure cap, the barrel being formed next to one end thereof with bypasses of a length for effecting fluid flow to 30 opposite sides of the piston when the latter is in juxtaposition to the said bypasses, and a sleeve-like member engaged with the barrel for accommodating the feeder member and pen point.
